Primary Examiner—Susan J. Lucas*Assistant Examiner*—Cynthia Ramirez*Attorney, Agent, or Firm*—Crowe & Dunlevy; Bill D. McCarthy**[57] CLAIM**

I claim the ornamental design for the support apparatus for trash bags, as shown and described.

DESCRIPTION

FIG. 1 is a perspective view of a support apparatus for trash bags showing my new design;

FIG. 2 is an elevational front view thereof, the rear elevational view being identical thereto;

FIG. 3 is an elevational view of one side thereof, the opposing other side being identical thereto;

FIG. 4 is a top plan view thereof; and,

FIG. 5 is a bottom plan view thereof.

The broken line showing of a bag in FIG. 1 is for illustrative purposes only and forms no part of the claimed design.
